(57) **CLAIM**

We claim the ornamental design for a cross-oriented bicycle cradle, as shown and described.

DESCRIPTION

FIG. 1 is a front elevational view of a cross-oriented bicycle cradle;

FIG. 2 is a left side elevational view thereof;

FIG. 3 is a top plan view thereof;

FIG. 4 is a bottom plan view thereof;

FIG. 5 is a perspective view thereof;

FIG. 6 is an upper perspective view thereof;

FIG. 7 is a lower perspective view thereof;

FIG. 8 is a first environmental perspective view thereof; and, FIG. 9 is a second environmental perspective view thereof.

The rear of the design is identical to the front of the design as illustrated in FIG. 1, and therefore is not shown. The right side of the design is identical to the left side of the design as shown in FIG. 2, and therefore is not shown. The broken lines are directed to environment and are for illustrative purposes only; the broken lines form no part of the claimed design.
